UNITED STATES PATENT OFFICE

WILLIS W. GARDNER, OF MERIDEN, CONNECTICUT

PNEUMATIC STOPPER FOR GAS MAINS

Application filed November 15, 1930. Serial No. 495,815.

My invention relates to an improved pneumatic stopper for use in given sections of gas-mains for checking the flow of gas therethrough as may be required preparatory to 5 new installations of gas-mains, to making alterations in existing gas-mains, and to kindred operations of whatever character requiring the temporary checking of the flow of gas through the mains, the object being to 10 produce, for the purposes indicated, a safe, simple and compact, quick and convenient device for inserting a bag into a gas-main without the escape therefrom of sufficient gas to overcome or even inconvenience the workmen employed. 15

With these ends in view, my invention consists in a pneumatic gas-main stopper having certain details of construction as will be hereinafter described and pointed out in the 20 claims.

In the accompanying drawings:

Fig. 1 is a view in elevation of a pneumatic gas-main stopper embodying my invention; 25 Fig. 2 is an enlarged broken sectional view thereof with the bag retracted into its housing;

Fig. 3 is a similar view showing the housing installed in a gas-main with the bag partly extruded thereinto from the housing; 30 Fig. 4 is a similar view showing the bag fully expanded within the gas-main, for which it forms a complete stop against the flow of gas therein;

Fig. 5 is an enlarged broken view in central 35 longitudinal section showing the mode of clamping the neck of the bag upon the air-pipe;

Fig. 6 is an enlarged transverse sectional view on the line 6—6 of Fig. 1;

Fig. 7 is an enlarged transverse sectional view on the line 7—7 of Fig. 4; and

Fig. 8 is a view in transverse section on the line 8—8 of Fig. 4.

In carrying out my invention as herein shown, I employ a bag-housing 10 consisting of a metal cylinder large enough to receive the bag 11 when it is collapsed, the said housing and bag being adapted in size to the size of the gas-main 12. The bag, which may be 45 of any approved construction and which con-

sists, as shown, of a rubber-body 13 having a canvas cover 14, is formed with a neck 15 which is clamped by a clip 16 upon the lower end of an air-pipe 17 thereto provided with a plurality of grooves 18 into which the material of the neck is forced, as shown in Fig. 5, by the constriction of the clamp. 55

The lower end of the cylindrical bag-housing 10 is externally threaded to adapt it to be screwed into a threaded hole 19 tapped in the gas-main at the point therein where the bag is to be introduced. After the removal of the "stopper," as such devices are commonly spoken of, this "tapping," so called, is closed by means of any suitable plug in the ordinary manner. 60

The upper end of the said housing 10 is threaded for the application of a threaded domical cap 20 forming a bearing for a plunger 21 which projects beyond it for a sufficient distance to provide for the play required for the ejection of the gas-bag into the gas-main. Near its inner end the plunger is threaded for the application of a packing-ring 22 held in place by nuts 23 located on opposite sides of it, this packing-ring preventing the escape of gas from the housing in the use of the "stopper." The outer end of the air-pipe 17 aforesaid projects beyond the outer end of the plunger and is provided 70 with a T 24 carrying a pressure-gauge 25 of any approved construction and having a nipple 26 containing any suitable air-valve 27 and providing for the attachment of a tube leading to any source of supply of gas under 75 pressure for the inflation of the gas-bag. 80

The neck 15 of the bag 11 receives a rubber-tube 28 which is directly clamped upon the grooved end of the air-pipe 17 by the clip 16 before described, as shown in Fig. 5, the 90 said clamp also clamping the said neck upon the pipe through the intermediary of the said tube. The tube 28, which thus virtually forms an extension of the bag, surrounds the air-pipe 17 nearly throughout its length and fits within the plunger 21, its projecting outer end being provided with a clamp 29 acting as a stop to prevent the air-pipe from being forced through the plunger when the same is forced through the housing in 95 100

jecting the bag into the gas-main. A stop-collar 30 mounted upon the plunger provides for limiting its inward movement with respect to the housing 10. To prevent any escape of gas through the plunger, I employ, as shown, a packing 31 applied over the lower end of the rubber-tube 28.

In the use of my improved device, the bag is normally housed entirely within the housing 10, where it is fully protected against injury in the transportation and handling of the "stopper," and also provides for that convenience of introducing the bag into the gas-main which constitutes the outstanding novelty and advantage of my invention.

In using the device, a hole is tapped at the desired point in the gas-main and the housing quickly screwed into it. The housing having been firmly mounted in the tapping as described, the plunger is forced downward in the housing until stopped by the collar 30 carried by it. At this time the bag is forced out of the housing into the main without any abrasion whatever of the bag, since its full course from the housing into the main is protected. When the bag has been forced into the main as described, air under pressure is applied to the nipple 26, whereby the bag is inflated until it fully fills the main, as shown in Fig. 4, so as to constitute a complete stop for the gas flowing through the same. It will be understood that the pressure of air introduced into the bag must be sufficient to expand it against the pressure of gas within the main. After the bag has been fully expanded it is sealed by the valve 27, or in any other convenient manner.

When the bag is introduced into the main, it may be displaced one way or the other out of center, as shown in Fig. 4, according to the direction in which the gas is flowing through the same, and dependent upon the pressure of the gas.

After the operation, whatever its character, has been finished, the valve 27 is opened, when the pressure of the gas in the main will deflate the bag. The housing is now unscrewed and the "stopper" as a unit removed from the main, the deflated bag passing readily through the "tapping," which is then plugged, with the escape of a minimum amount of gas.

Generally, more than one of these "stoppers" is used at the same time, dependent upon the character of the work being done.

It will be seen from the foregoing description that the introduction of the bag into the main is effected with the utmost facility, without the escape of an amount of gas imperiling the safety of the workmen and without any danger of mutilating the bag, as distinguished from methods in use prior to my invention, which necessarily involve the double "tapping" of the main and the escape of

a relatively large amount of gas during the manual manipulation of the bag in order to drag it into the main through one "tapping" by a cable inserted into the other "tapping."

My improved device is primarily designed for use as a "stopper" for gas-mains and may be adapted to high, low, and intermediate pressures of gas. It may also be used to advantage in water-mains. And I would have it so understood.

I would also have it understood that in practicing my invention, changes may be made in the device herein shown and described, without departing from the spirit and scope of my invention.

I claim:

1. A portable pneumatic stopper for gas-mains, having a cylindrical bag-housing threaded at its inner end for direct application to a tapping in a gas-main, a plunger located in the said housing, a plunger-bearing applied to the outer end of the said housing, a packing located at the lower end of the plunger and co-acting with the inner wall of the housing, a flexible bag firmly connected directly with the inner end of the plunger and adapted to be retracted into the housing thereby, and means for causing the inflation of the said bag after the same has been ejected into the gas-main by plunger.

2. A portable pneumatic stopper for gas-mains, having a cylindrical bag-housing threaded at its inner end for direct application to a tapping in a gas-main, a plunger located in the said housing, a bearing at the outer end of the said housing for the said plunger, a packing carried by the inner end of the plunger and cooperating with the inner wall of the housing, a flexible bag firmly fixed directly upon the inner end of the plunger and adapted to be retracted into the housing thereby, means for causing the inflation of the bag after the bag has been ejected by the plunger into the gas-main, and a pressure-gauge located at the outer end of the plunger.

3. A portable pneumatic stopper for gas-mains, having a cylindrical bag-housing threaded at its inner end for direct application to a tapping in a gas-main, a plunger located in the said housing, a bearing at the outer end of the said housing for the said plunger, a packing carried by the inner end of the plunger and cooperating with the inner wall of the housing, a flexible bag firmly fixed directly upon the inner end of the plunger and adapted to be retracted into the housing thereby, means for causing the inflation of the bag after the bag has been ejected by the plunger into the gas-main, and an adjustable stop mounted upon the plunger for predetermining the positioning of the ejected bag in the gas-main.

4. A portable pneumatic stopper for gas-mains, having a cylindrical bag-housing threaded at its inner end for direct applica-

tion to a tapping in a gas-main, a plunger located in the said housing, a bearing at the outer end of the said housing for the said plunger, a packing carried by the inner end of the plunger and cooperating with the inner wall of the housing, a flexible bag firmly fixed directly upon the inner end of the plunger and adapted to be retracted into the housing thereby, means for causing the inflation of the bag after the bag has been ejected by the plunger into the gas-main, a pressure-gauge located at the outer end of the plunger, and an adjustable stop mounted upon the plunger for predetermining the positioning of the ejected bag in the gas-main.

10 In testimony whereof, I have signed this specification.

WILLIS W. GARDNER.
